COMBINATION MEMORANDUM PAD AND
ILLUMINATING DEVICE

Alfred Matlitzki, New York, N. Y.

Application August 8, 1938, Serial No. 223,740

3 Claims. (Cl. 240—6.4)

This invention generally relates to a combination writing or like implement and electric illuminating apparatus or unit, and more particularly to memorandum pads the surface of which may be illuminated for writing or other purposes in dark rooms or places during night time by the afore-mentioned apparatus.

It is an object of this invention to provide a practical, economical and inexpensive device of the above nature.

Another object of the present invention resides in the provision of an electric lighting device in cooperation with a writing pad or the like whereby said device may be controlled at will by the pencil or like instrument used in connection with the pad.

It is still another object of this invention to provide switch means to control said lighting device.

A further object of the present invention contemplates the provision of a pencil which may be brought into operative or inoperative position in said switch means for the aforementioned purpose.

Still another object of this invention is to provide means to control the said unit, and a member adapted to actuate said means, said member for connecting and disconnecting said means with said unit respectively upon releasing of said member from said means.

Still another object of this invention is to provide a member for selectively connecting and disconnecting said means and said unit respectively.

A still further object of this invention is to provide a catch associated with said switch means to intermittently engage said member for controlling said means.

The above and other objects of the invention and the means for their attainment will be more apparent from the following detailed description taken in connection with the accompanying drawing illustrating a preferred embodiment by which the invention may be realized and in which:

Fig. 1 is a top plan view of a pad provided with a casing for housing an electric illuminating unit therein.

Fig. 2 is a sectional side view along line 2—2 of Fig. 3.

Fig. 3 is a bottom plan view of the device of Fig. 1.

Fig. 4 is a perspective fragmentary view of the switch portion in inoperative position.

Fig. 5 is a perspective fragmentary view similar to Fig. 4, the switch being shown in operative position.

Fig. 6 is a perspective view of the pencil with its flat portion thereon.

Figs. 7-10 inclusive show diagrammatically the different positions of the switch actuated by the pencil.

Referring now to the drawing, the writing implement 10 which may be made of any suitable material, as for example of a plastic material, metal or the like, comprises the compartment 11 for receiving a loose leaf paper pad 12 therein and the casing 13 which may be associated with said compartment 11. Casing 13 accommodates on support 21 an electric dry cell battery 14 for supplying electric current through the connections 14', 22, 23 to the incandescent lamp or bulb 15 located on a switch block 16 within said casing 13. Bulb 15 protrudes from said block 16 through an opening in wall 17 in such manner so as to illuminate the top sheet 18 of said pad 12, if desired. To this end, wall 19 of said casing 13 is curved and provided with an arcuate portion 20 at its upper end to direct and reflect light rays emitted from said bulb toward the surface of the top leaf 18 of said pad 12.

5 10 Switch block 16 which carries the leaf spring contact bars 22, 23 may be made of a suitable insulating material and has in its base portion 24 a lodgement or bore 25 for receiving therein a pencil 26. Pencil 26 is provided with a flat part

15 20 25 27 for a purpose hereinafter set forth.

The contact bar 23 is secured at one end to block 16, as at 23' and is adapted for spring engagement with contact bar 22. Block 16 has a cut-out 16' for the reception of the inwardly

30 35 40 bent or looped portion 22'' of bar 22. Communicating with the core 25 is an opening 16''.

If the pencil 26 is inserted within the bore 25 the looped portion 22'' of the bar 22 will abut against the pencil 26 causing the bar 22 to be flexed outwardly and its end 22' out of engagement with the contact bar 23 thus breaking electrical connection. In order to maintain this disconnection, that is, to maintain the switch in inoperative position the following provision is made:

45 50 55 60 Provided on block 16 is a catch or trigger 28 which may consist of a bar 29 made of springy material and which is fixedly secured at its one end to block 16 by suitable means, such as a screw 30. Its free other end 31 is provided with a projection 33 adapted for engagement with bar 22 for maintaining the latter out of contact with bar 23 in the inoperative position. The bar 29 is provided with an abutment 32 which extends through an opening 32' into bore 25 of block 16.

By the insertion of pencil 26 within bore 25 and in engagement with abutment 32 the catch 28 is flexed outwardly and the looped portion 22'' of bar 22 is in engagement with pencil 26 through opening 16'', as shown in Fig. 7.

If the pencil is now rotated in bore 25 until its flat portion (which is on a lower plane than its arcuate portion) is adjacent the looped portion 22'', the latter will be caused to retract. During this retraction catch 28 is flexed thus allowing the bar 22 to freely contact bar 23 without being

interfered with by the projection 33, as shown in Fig. 10.

Fig. 9 shows the relative positions of pencil 26, looped portion 22" of bar 22, and catch 28 during a stage of operation.

To cause disconnection of contact bars 22 and 23, the pencil 26 is inserted within bore 25 causing thereby the catch 28 and bar 22 to flex sufficiently outwardly to allow the edge of the bar 22 to clear the projection 33 of catch 28. After this clearing has been accomplished and the pencil withdrawn, catch 28 will automatically retract, thereby causing the projection 33 to support bar 22 against contact of the latter with the bar 23 and thus maintaining disconnection of the current. The catch 28 is caused to retract earlier than bar 22. It is to be observed that, when inserting the pencil 26 for disconnection of the switch the flat portion 27 should not be opposite the looped portion 22", otherwise the releasing action could not be accomplished.

It can be readily seen that the above electrical switch arrangement may be adapted for other uses and therefore is not intended that it be limited to the aforesaid application. This switch arrangement may be employed in any part of an electric circuit whereby connection and disconnection of the circuit is desired by the manipulation of a member or key in a manner or similar to that explained hereinabove.

In order to make accessible the parts within housing 13, there is provided a removable bottom plate 40. Plate 40 is supported at one end by a flange 41, the other end of plate 40 being supported by the lugs 42. By swinging these lugs 42 about their pivots 43 bottom plate 40 may be readily withdrawn with its parts mounted thereon.

Pad 12 may be of the type wherein a binding strip 12' is employed to keep the sheets of said pad together. The pad is preferably placed with its strip 12' against wall 11' whereas the other loose end of the pad is releasably held by any suitable resilient means, such as springs 44. If it is desired to remove the top sheet from said pad, said sheet is frictionally engaged with a finger of a hand and withdrawn from under the spring means 44 and then separated from said strip. Of course, it is understood that a new pad may be easily and readily inserted within the compartment 11 after a previous pad has been used up.

Any suitable design may be applied to the casting 13 and a section 45 may be used for receiving a name plate or any desired engraving.

In order to fix the position of the pencil, particularly during darkness, there is provided a flat surface D on the projecting end of the pencil and which is in alignment with flat surface 27. By these means the operator can easily feel the location of the flat part for its purpose, namely to engage the looped portion 22" of bar 22 with the flat surface 27 of the pencil, releasing the catch 28 as set forth above.

From the foregoing description, taken in connection with the accompanying drawing, the advantage of the construction and operation of the device shown will be readily understood by those skilled in the art to which the invention pertains; and while I have described the principle of operation, together with the device which I now consider to be the best embodiment thereof, I desire to have it understood that the device shown is merely illustrative and that such

changes may be made as are within the scope of the appended claims.

Having thus described the invention what is claimed as new and desired to be secured by Letters Patent is:

1. In a writing pad device and the like having an electric lamp for illuminating the surface of said pad; a switch block provided with a bore and carrying said lamp, a member provided with a flat part, said member being removably slidable in said bore, contact bars mounted on said block for conducting current from a supply source to said lamp, one of said bars being movable relatively to the other of said bars and having a looped portion, said block having an opening and a cut-out, said opening and said cut-out communicating with said bore, and catch means on said block and provided with a projection, said looped portion protruding through said cut-out and said projection extending through said opening into said bore, said looped portion and said projection being actuatable by said member to connect and disconnect contact between said bars, said catch means being adapted to maintain said contact disconnection upon engagement of said projection with said flat part of said member and subsequent sliding movement of said member along and out of said bore.

2. In a device of the character described having a writing pad and the like, a lamp for illuminating the pad surface, a pair of contact bars one movable relatively to the other for connecting and disconnecting electric current supply to said lamp, and a writing member for said pad and engageable with one of said contact bars; a support having a bore for slidably receiving therein said member, said member being provided at the circumference thereof with two portions in different planes, and catch means mounted on said support, said catch means and said one contact bar being actuatable by said member and separated from each other upon insertion of said member in said bore, said one contact bar when in contact with one of said portions and upon sliding movement of said member longitudinally of said bore engaging the other of said bars and connecting said lamp to said current supply, said one contact bar when in contact with the other of said portions of said member and upon sliding movement of said member longitudinally of said bore engaging said catch means and remaining out of engagement with said other of said contact bars thus disconnecting said lamp from said current supply.

3. In a device of the character described having an electric illuminating unit; a pair of engageable contact bars joined through a circuit to an electric current supply source and adapted to respectively open and close said circuit to which said unit is connected, a catch adjacent one of said contact bars and provided with a projection, and a member provided with two faces at relatively different levels, respectively, said member being removably positioned adjacent said one contact bar and said catch, said faces being engageable, respectively with said projection and a portion of said one contact bar, whereby upon removal of said member with its faces from respective engagement with said projection and said contact bar portion, said one contact bar may engage selectively with said catch to interrupt the circuit or clear said catch for engagement of said one with the other contact bar to close said circuit.

ALFRED MATTIATZKI.
